UNITED STATES PATENT OFFICE.

ERNEST EMERSON, OF CHICAGO, ILLINOIS, ASSIGNOR TO WIREBOUNDS PATENTS COMPANY, OF KITTERY, MAINE, A CORPORATION OF MAINE.

MACHINE FOR USE IN MAKING BOXES.

Application filed December 5, 1919. Serial No. 842,757.

To all whom it may concern:

Be it known that I, ERNEST EMERSON, a citizen of the United States, residing at Chicago, in the county of Cook, in the State of Illinois, have invented new and useful Improvements in Machines for Use in Making Boxes; of which the following is a specification.

The invention relates to machines for use in making boxes and particularly to machines for use in making wirebound boxes, crates, blanks or parts thereof.

Among other objects the invention is intended to provide a machine of the class described having improved means for severing the binding wire between successive box assemblies or parts.

The nature of the invention will be best understood by reference to one form of machine containing an embodiment thereof, which is shown for illustration in the accompanying drawings.

The machine selected for illustration is a wire-bound box blank machine adapted for uninterrupted operation in making a number of wirebound box blanks in succession, continuous lengths of binding wire being applied to successive assemblies of box materials; and the purpose of the invention in such illustrative embodiment is to sever the binding wire between successive assemblies of box parts.

Obviously the invention is not limited in its application to machines of this particular type.

In the drawings: Figure 1 is a side elevation of the illustrative box blank machine, omitting the receiving end of the work conveyor.

Fig. 2 is an end elevation, looking at the delivery end of the machine.

Fig. 3 is a detailed view of a cutter in operative position viewed from the delivery end of the machine.

Fig. 4 is an enlarged side elevation of a cutter showing its attachment to the machine in operative and inoperative positions.

Figs. 5, 6, 7 and 8 are diagrammatic views illustrative of the operation of a cutter.

Fig. 9 is a detailed view of a cutter in operative position showing the gauging means for positioning the point of cut-off.

The illustrative machine comprises, between supporting side frames 1, a gang of

staplers 2 and a relatively movable work-holder 3 for assembling cleats 50 and side material 51 for a box blank or a succession of foldably related box sections.

The work-holder 3 is in the form of a circulating conveyor having work-positioning means for a succession of blanks; said conveyor comprising a pair of endless link chains properly channel-shaped to receive the box cleats and having spacer blocks 4 affixed thereon, at intervals, for determining proper relationship of adjacent box sections, or of the cleats and side material for a blank, and for spacing successive blanks apart.

Box sections are successively assembled on the conveyor chains by placing cleats 50 thereon, in pairs, and laying sheets of side material 51 thereacross, or, if desired, slatted side material for a crate blank may be laid across said cleats, or an integral sheet of side material for a blank may be placed upon a succession of cleats.

The conveyor chains run on horizontal guide rails 5 and at the delivery end of the machine are trained around the driven sprocket wheels 6, which may be rotated from the main shaft 7 by any suitable means, for instance, by the ratchet feed mechanism shown in Fig. 1, comprising ratchet wheel 8 and co-acting feed pawl 9 carried by lever 10, which is operated through rod 11 from eccentric 12.

With the type of feed mechanism described, the conveyor and work thereon will be advanced to the staplers, step-by-step, in alternation with the stapling operations; and associated with said mechanism there may be provided any suitable devices, not necessary to be illustrated, for varying, adjusting or controlling the feed, for skipping the stapling operation at the box joints, for manually, independently rotating the conveyor sprockets for initial work adjustment or otherwise, and for braking the conveyor sprockets at the completion of each feed step.

Suitable means for these purposes are shown for example in the patent to Thompson No. 1,258,625 dated March 5, 1918, and in the pending application of S. F. Bauwens filed March 22, 1919, being application Serial No. 284,332.

As the work progresses beneath the sta-

plers, a plurality of continuous lengths of binding wires 13, drawn from suitable supply reels, not shown, are introduced in proper relation to the box sections to be 5 stapled thereto, the wires being led between the rollers 14 and thence under the rollers 14 at the feet of the stapler bodies, and being pulled along with the work by virtue of their attachment thereto at preceding points. 10 Certain of the wires aligned with the box cleats are stapled through the sheets thereto, so as to connect such wires to both the sheets and cleats and secure the latter together; and intermediate wires are or may 15 be stapled to the sheets alone and clinched on the under sides by the co-action of the staple drivers with anvils 16 supported on the cross frame 17.

The staplers 2 may be of the type 20 closed, for example, in the aforesaid patent to Thompson No. 1,258,625, dated March 5, 1918, comprising combined staple formers and drivers adapted at every operation to 25 cut and form staples from staple stock wire 18, fed thereto by rollers 19, and to drive the same over the binding wires into the work. Said staplers are mounted on the stationary cross head 20 and are actuated by the vertically reciprocating cross bar 21 30 working in guides of the side frames 1 and operated by a pitman 22 from eccentric 23 on the main shaft, there being similar operating connections at either side of the machine. The feed rollers 19 for the staple 35 stock wires are also operated from the main shaft by eccentric 24 and connecting rod 25 working a pawl and ratchet device 26 for rotating the rollers intermittently.

With the intermittent feed type of machine described, a staple is formed and driven at every reciprocation of the cross head 21 or so-called "upper stitcher bar," the staple being driven on the downward stroke thereof, while the material is momentarily 45 at rest, the extent of movement of the material between the successive operations of the staplers determining the spacing between successive staples.

It will be understood that the specific machine here illustrated is but one illustrative example of a machine to which the invention is applicable, in which box parts are successively wired together by effecting relative progression between work and fastener-setting mechanism, and in which desired relative positions of adjacent box parts are properly maintained during the wiring of such parts together; various constructions and arrangements for these functions being 60 already known to the art.

Referring again to the illustrative machine, as the work leaves the stapling mechanism, the finished blank may be stripped from the conveyer chains on to the stripper 65 bars 27, and the wires connecting one blank

with another may be severed by the automatic cutting mechanism presently to be described.

The binding wires are intended to be severed between one blank or group of box 70 parts and the next in such a manner as to leave free wire ends projecting beyond the ends of the blank so that when the blank is folded into box form, these projecting wire ends may be twisted or otherwise secured 75 together to close the box. To suit this purpose the materials for succeeding blanks are suitably spaced to leave between them a sufficient length of wire to provide, when severed, the desired free ends. Such spacing 80 may be effected, for example, by placing the first spacer block for a box blank the desired distance in the rear of the last spacer block for the preceding blank or by inserting 85 elongated spacers between successive blanks. 90

Mechanism for severing the binding wires is arranged at the delivery end of the machine and preferably at such a distance from the stapling plane as to insure the driving of a plurality of successive staples, three for instance, in each blank before severing the wires; thus the wires will be firmly held 95 against slipping during the severing operation.

The illustrative wire severing mechanism 95 comprises a gang of individual wire cutters 28, corresponding in number to the staplers, and arranged directly behind the staplers in the line of travel of the work. Said cutters are normally maintained in inoperative or 100 inactive position, and are adapted upon presentation of a cutting space between blanks or other pieces of work, to enter said spaces and engage and cut the wires.

As shown the cutters are hung from a 105 rocker shaft 29, supported at either side of the machine by notched arms 31, so as to drag over the work and be held thereby in non-cutting position, and so as to drop or swing into a space between blanks when such 110 space is presented, and after the wire-severing operation to be again raised to normal non-cutting position by the advancing movement of the following blank. This is an especially desirable arrangement for work 115 control of the cutting operation, in accordance with relative progression of the work; in such arrangement the swinging cutter bodies, or at least one of them, if the several 120 cutter bodies are as shown, splined to shaft 29, typify a controller responsive to the passage of each of successively passing blanks or other pieces of work to be cut apart.

While said cutters will ordinarily drop or swing into the spaces between box assemblies 125 by force of gravity, to insure against possible failure, a positive means for swinging said cutters into operative position may be provided.

Such a means may comprise a spring 47 130

suitably secured to the frame of the machine and connected to the lower end of a lever arm 48 splined to the shaft 29 as shown in Figure 4.

5 To gauge and position the cutters from the edge of the oncoming box blank or box part, when in operative position, and to hold the cutting knives and associated parts above the passing work, when in inoperative position, a gauge or shoe 45 is secured to a bracket 46 carried at the lower end of the casing 33, which gauge 45 is so formed as to pass between the spacer blocks 4 and the outer channel flange of the conveyer chain 10 when the cutter swings into operative position, and abut against the edge of the oncoming work. Said gauge may be appropriately formed to position the point of cut-off, relative to edges of the work, where desired. When all of the cutters are splined to the shaft 29, as shown in the illustrative machine, it is preferable to secure the gauge or shoe 45 to the outside cutters only. It will be noted that the gauge 45 of the outer 15 side cutters rides directly over the cleats so that when the cutters are riding, in inoperative position, on slatted side material for a crate, the cleats will support the cutters and prevent them from dropping into operative 20 position between such slats.

The individual cutters which are splined to rock shaft 29 each comprise a slidable bar shaped knife 35, having its cutting edge at the lower end; a spring pressed knife 36, 25 having its cutting edge on the upper side, adapted to cooperate with knife 35 to sever the wire therebetween and means for causing cooperation of said knives. As shown in Figs. 3 and 4 knife 35 slides in channel 30 34 formed by the casing 33 and is held in proper position therein by spring 37 secured to the head of said casing, which said spring is so adjusted as to hold the cutting or lower edge of knife 35 above the wire when the 35 cutter swings into operative position as shown in Fig. 3. Knife 36 which is slidably mounted in bracket 38 secured to casing 33 is yieldingly held in operative position by a spring 39. Movement of knife 40 36 to the left in Fig. 3 is limited by pin 41 which engages the bracket 38. Knife 36 is beveled on its underside, as shown in Fig. 3, so that when the cutter swings down into operative position against the oncoming 45 work, the taut wire between box assemblies will force the knife to one side against the action of spring 39 and pass above the knife as shown in Fig. 3. Knife 36 by the action of spring 39 will immediately snap in 50 under the wire which will then be lodged below knife 35 and above knife 36 in position for the severing operation as best shown in Figs. 3, 7 and 9.

To cause said knives to cooperate and 55 sever the wire therebetween the cutter is

provided with mechanism to cause relative movement between the cutting edges of said knives when the cutter is moved by the action of the moving work.

Suitable mechanism for such purpose consists of a pawl 32, pivoted on shaft 30 carried by the bracket 31, yieldingly held in contact with the knife 35 by spring 44 so as to cooperate with a lug 42 carried by knife 35 as will now be explained. As shown in Fig. 4 shafts 29 and 30 are so located relative to each other that the pawl 32 and the knives 35 and 36 with their associated parts pivot on different centers. The parts are so related that when the cutter swings into operative position shown in dotted lines in Fig. 4 pawl 32 will take the position there shown directly above the lug 42 and when cutter 28 swings to the left from the vertical position shown in dotted lines in Fig. 4 pawl 32 will engage lug 42 carried by knife 35 and the swinging motion of the pawl relative to the swinging motion of the knife 35 will produce relative movement between knife 35 and knife 36, that is to say, as the work pushes the cutter to the left from dotted line position in Fig. 4, knife 36 following its arc of travel will rise while the knife 35 held by pawl 32 and following the arc of travel of the pawl 32 will be lowered until the cutting edges of the knives meet and pass each other severing the wire therebetween.

Thus it will be seen that the cutter moves with the work during a severing operation, 100 and that such movement automatically severs the binding wire.

This is particularly advantageous in that it obviates the necessity of providing independent actuating mechanism for the cutter 105 properly timed to operate in correlation with the movement of the work and the staplers, the cutter automatically operating without adjustment at proper times as the work progresses regardless of the action of 110 the staplers and the intermittent feed of the work.

For releasing the pawl 32 from lug 42 after the severing operation knife 35 is provided with a cam surface 43 located directly 115 above lug 42 and adapted to throw pawl 32 from engagement with lug 42 as the cutter swings upward by the continued movement of the work to assume the position on the work shown in full lines in Fig. 4. When 120 pawl 32 is disengaged from lug 42 by the action of the cam surface 43 knife 35 is returned to normal position by means of the spring 37. The cutter continues to ride on top of the box materials until the next space 125 between box assemblies or box parts presents itself. As it again swings down into operative position against the oncoming box assembly pawl 32, snaps in above lug 42 in position to engage lug 42 when the cutter 130

is again actuated by the oncoming box assembly.

In connection with Fig. 4 the diagrammatic views of Figs. 5, 6, 7 and 8 will clearly explain the operation.

Fig. 5 indicates the position of the parts when in the downward swing of the cutter. The taut binding wire has just engaged the lower beveled surface of the knife 36 to move it to the right in Fig. 5.

Continued descent of the parts is represented in Fig. 6 wherein the wire is displacing the knife 36. Thus the parts are brought to the position shown in Fig. 7, the knife 36 having snapped back beneath the wire and the wire being in position for severing between knives 35 and 36.

Fig. 8 shows the wire severed between knives 35 and 36 by the movement of the cutter which causes the shearing edge of the knife 35 to pass the shearing edge of the knife 36.

After the severing operation the movement of the work swings the cutter upward until it rests upon the oncoming blank where it rides until another space between blanks presents itself.

It will be noted that the cutter is actuated by the movement of the work and operates while the work is moving. It will also be noted that the point of cut-off is always at a fixed distance from the edge of the work and from the stapling plane, said point of cut-off being controlled by the gauge which contacts with the initial edge of the work.

Among other obvious advantages of the mechanism described the cutters will operate uniformly in relation to each of successively presented pieces of work, adjusting themselves to the work so that if by reason of irregularity in work-feeding, there should be variations in the position at which the cutting space is presented, the cutters will accommodate themselves thereto and will cut off the wires at the point predetermined by the gauge, for which different sizes may be substituted according to the desired point of cut-off.

It will be noted further that the cutting operation is controlled and actuated by the work itself and that said operation is not dependent upon any independent mechanism timed to sever the wires at proper intervals. An advantage of this arrangement among others is that the cut-off will operate to sever the wires uniformly at desired points relative to the edges of the work, automatically without adjustment.

Obviously, the present invention is not limited to the particular embodiment shown and described, but may be variously embodied and the particular construction shown may be variously modified as will appear to those skilled in the art. Furthermore, it is not indispensable that all the features of the

invention be used conjointly, since they may be used to advantage in various different combinations and sub-combinations.

I claim—

1. A machine for use in making boxes comprising, in combination, work-feeding means, fastener-setting mechanism for applying binding wire to box parts, and wire-severing means actuated by the work in its movement. 75

2. A machine for use in making boxes comprising, in combination, work-feeding means, fastener-setting mechanism for applying binding wire to box parts, and wire-severing means adapted to ride on the box parts, enter spaces therebetween and be actuated by the work in its movement. 80

3. A machine for use in making boxes comprising, in combination, work-feeding means, fastener-setting mechanism for applying binding wire to box parts, and wire-severing means adapted to ride on the work, to automatically enter the spaces between box parts and move with the work during a severing operation. 85

4. A machine for use in making boxes comprising, in combination, work-feeding means, fastener-setting mechanism for applying binding wire to box parts, and wire-severing mechanism adapted to enter spaces between box parts and be actuated by the work in its movement. 90

5. A machine for use in making boxes comprising, in combination, work-feeding means, fastener-setting mechanism for applying binding wire to box parts, and means normally maintained above the work and adapted to enter a space between box parts and by contact with the moving work to be moved thereby to sever the wire. 100

6. A machine for use in making boxes comprising, in combination, work-feeding means, fastener-setting mechanism for applying binding wire to box parts, and wire-severing means normally held in inoperative position but adapted to enter the spaces between box parts and be actuated by the box parts in their movement to sever the wire therebetween. 110

7. In a box blank machine, the combination of devices to form spaces at intervals in the materials, mechanism to fasten binding wire to the materials, a device for cutting said wire in said previously formed spaces, said cutting device being actuated by the work in its movement. 115

8. A machine for use in making wirebound boxes comprising, in combination, work-feeding means, mechanism for securing binding wire to box parts, and means for cutting said wire controlled by the work and moving therewith during a wire-severing operation. 125

9. A machine for use in making wirebound boxes, comprising, in combination, work-feeding means, mechanism for securing binding 130

- wire to box parts, and means actuated by the work for cutting said wire upon the passage of a space opposite said cutting means.
10. A machine for use in making wire-bound boxes comprising, in combination, work-feeding means, means to secure binding wire to box parts, and means actuated by the work in its movement to sever said wire between box parts at a predetermined point 10 relative to the edge of a box part.
11. In a machine of the class described having relatively movable work and wire securing means by which binding wire is progressively applied to the work, means, 15 dragging on the work, adapted to enter spaces therein and sever binding wire between successive pieces of work while moving therewith.
12. A machine for making wirebound 20 boxes comprising, in combination, means to secure binding wire to box parts, means to sever said wire between box parts, comprising a pivoted cutter adapted to ride on the box parts, swing into cutting position between box parts, and move with the box parts during a cutting operation.
13. A machine for use in making wire-bound box blanks comprising, in combination, means to secure binding wire to successive 25 box blanks, and means adapted to ride on the blanks and controlled and actuated by their passage through the machine for severing the wires therebetween.
14. A machine for use in making wire-bound boxes comprising, in combination, fastener-setting mechanism to secure binding wire to box parts, means to cause relative progression between the work and fastener-setting mechanism, and cutting means 30 adapted to be positioned and actuated by the work.
15. A machine for use in making boxes comprising, in combination, work-feeding means, fastener-setting mechanism for applying binding wire to box parts, and wire-severing means actuated by the work, including gauging means for positioning the severing means for a severing operation.
16. A machine for use in making boxes 40 comprising, in combination, work-feeding means, fastener-setting mechanism for applying binding wire to box parts, and wire-severing means actuated by the work, including work-engaging means for determining the point of cut-off relative to the edge of a box part.
17. A machine for use in making wire-bound boxes comprising, in combination, means to secure binding wire to box parts, 45 and wire-severing means movable with the work during a severing operation, including a gauge carried thereby and adapted to successively position said severing means for a cutting operation relative to the edge of each 50 of successive pieces of work.
18. In a machine for use in making wire-bound boxes the combination of means to secure binding wire to box parts, means to cause relative progression between said mechanism and the work, and a binding wire cutter comprising a connected pair of relatively movable knives operable upon movement of said cutter in the direction of travel of the work.
19. In a machine for use in making wire-bound boxes the combination of means to secure binding wire to box parts, means to cause relative progression between said mechanism and the work, and a binding wire cutter comprising cooperating knives normally maintained above the work and operable upon movement of said cutter in the direction of movement of the work.
20. In a machine for use in making wire-bound boxes the combination of means to secure binding wire to box parts, means to cause relative progression between said mechanism and the work, and a binding wire cutter comprising connected cooperating knives relatively movable upon movement of said cutter with the work.
21. A machine for use in making boxes comprising, in combination, work-feeding means, mechanism for applying binding wire to box parts, and binding wire-severing means adapted to enter spaces between box parts comprising connected cutting members automatically operable by movement of said wire-severing means with the work.
22. A machine for use in making boxes comprising in combination, work-feeding means, mechanism for applying binding wire to box parts, and binding wire-severing means including a vertically reciprocating cutter automatically operable by movement of said means in the direction of the movement of the work.
23. A machine for use in making boxes comprising, in combination, means for applying binding wire to box parts and wire-severing mechanism comprising a pair of relatively movable cutting members normally maintained above the plane of the work, one such member being adapted to assume a cutting position below a wire and to cooperate with the other member upon movement of the severing mechanism in one direction.
24. A machine for use in making boxes comprising, in combination, means for applying binding wire to box parts and wire-severing mechanism comprising a pair of relatively movable cutting members normally maintained above the plane of the work, one such member being adapted to assume a cutting position below a wire and to cooperate with the other member upon movement with the work.
25. A machine for use in making boxes

130

- comprising, in combination, means for applying binding wire to box parts and wire-severing mechanism comprising a pair of relatively movable cutting members normally maintained above the plane of the work, one of said members being adapted when lowered against a wire to assume a cutting position beneath said wire and said members being adapted to cooperate when moved in the direction of travel of the work.
26. A machine for use in making boxes comprising, in combination, work feeding means, binding wire applying mechanism, and wire-severing means actuated by the work.
27. A machine for use in making wire-bound boxes comprising, in combination, binding-wire-applying mechanism, means to sever the binding wire between box parts, a support for said severing means, and means to cause relative progression between said support and the box parts; said severing means being pivotally hung from said support and adapted to engage a box part edge and operable by said relative movement.
28. A machine for use in making wire-bound boxes comprising, in combination, binding-wire-applying mechanism, means to sever the binding wire between box parts, a support for said severing means, and means to cause relative progression between said support and the box parts; said severing means being pivotally hung from said support and adapted to enter a space between box parts and to engage a box part edge and operable by said relative movement.
29. A machine for use in making wire-bound boxes comprising, in combination, binding-wire-applying mechanism, means to sever the binding wire between box parts, a support for said severing means, and means to cause relative progression between said support and the box parts; said severing means being pivotally hung from said support and adapted to engage a box part edge and comprising a pair of relatively movable cutting members normally maintained above the plane of the work one such member adapted to assume a cutting position beneath the binding wire and to cooperate with the other member upon relative movement between the box parts and said support.
- In testimony whereof, I have signed my name to this specification.

ERNEST EMERSON.
